UNITED STATES PATENT OFFICE.

THEODORE A. PALM, OF WHITE HOUSE, PENNSYLVANIA.

WHEEL-CULTIVATOR.

SPECIFICATION forming part of Letters Patent No. 252,794, dated January 24, 1882.

Application filed August 26, 1881. (Model.)

To all whom it may concern:

Be it known that I, THEODORE A. PALM, of White House, in the county of Cumberland and State of Pennsylvania, have invented certain Improvements in Wheel-Cultivators, of which the following is a specification.

This invention relates to certain improvements in wheel-cultivators, which will be hereinafter described, and set forth in the claims.

10 Figure 1 is a plan view of the cultivator containing the improvements. Fig. 2 is an end view of the same in the rear. Figs. 3, 4, 5, 6 are details of the several parts. Fig. 7 is a sectional view of the wheel-spindles and the 15 axle-tree stock with the wheel removed. Fig. 8 is a side view of the cultivator in part, showing the connecting-bars which sustain the back rod for moving the wheels.

A is an axle-tree stock, to which is attached 20 the shaft or pole, which in this case is bifurcated to give stiffness to the whole frame.

A' A' are bent axle trees or spindles, which are bolted to the under side of the axle-tree stock A at each end, and on which axle-trees 25 A' A' are supported wheels A² A².

B B, &c., are plow-points or shovels, which are supported by bolts on U-shaped bracket-pieces b b, &c., Fig. 3, which at their upperends are bent over like a hook, and in the curved 30 part having a hole, b', through which is a rod, c, passing through the plow-point standard C and through springs c'. These bracket-pieces b b are pivoted within other bracket-pieces, C' C', which are U-shaped and bolted fast to the 35 standards C C. It will be seen that by this arrangement of the plow-points B B they are able to spring to a certain extent and yield as they encounter the inequalities of the ground and avoid being broken, as is often the case 40 otherwise.

D is a rod of metal, which extends across the machine in the rear of and parallel to the axle-tree stock A, and which connects two bars, D' D', that are pivoted at the ends of 45 the stock A on two upright rods, a a, which are fastened to and sustained by the bent axles or spindles A' A', and in plates a' a', which are bolted to the ends of A.

a² is a brace-rod, which is socketed on one 50 of the bars D', and is hooked into the frame I

at i whenever it is desired to keep the frame in its stationary position, or in moving to or from the field, as shown in solid lines, Fig. 1. When used in plowing this rod a² is to be removed to permit the wheels to be turned, as seen in 55 broken lines in Fig. 1.

D³ D³ are curved yokes, which are attached to the rod D, and which are designed for the feet while the driver is seated. When he is walking behind the cultivator he moves the 60 frame with his hand by the handle H, which is attached to one of the yokes D³ and pivoted to the stock A, but when riding the handle can be removed.

Fig. 3 represents the manner of constructing 65 and arranging the plow-beams and standards and the frame by which the beam is elevated or depressed to lift the plow-points out of the ground or let them down for work to any depth.

G is the beam, C C the standards, and B B 70 the plow-points, as before described.

E E are grooved straps attached to the side of the beams, having the slots e e therein and bolts to fasten the straps E E, and yet allow them to slide to the extent of the slots, so that 75 either beam can rise and fall over any obstacle, when encountered, independently of the other. These straps E E unite at top and are bolted to the end of a bell-crank handle, E', which is pivoted to the middle of the axle-tree stock A. 80 This handle E' has on one side a pin, k, and there is a spring-catch K which holds the handle by the pin k when in the position shown in dotted lines in Fig. 3, when the beam G will be held up, as also seen in dotted lines, and 85 with it the plow-points, which will then be out of the ground and some distance above it. (Not shown in Fig. 3.) The plow-beams have a bifurcated strap, g, which is pivoted to the under side of the cross-beam L on rods F F suspended 90 beneath L, as seen in Fig. 6, from adjustable brackets l l, which can be made to move to right or left within a certain compass by means of slots in them, and set-screws for the purpose of shifting the shovels or plow-points to or 95 from the rows. The straps g g are the clevises, which can be adjusted to run the plow-points deep or shallow by shifting the bolt-holes in the end of the beams G.

M is the driver's seat on the frame I, which 100

frame and seat are so constructed as to be readily removed. When the driver is to walk side boards, N, are attached to the shovels.

The spindles or bent axles A' A' are attached 5 to the rod D by means of brace-rods D² D² immediately under the bars D' D', which rods D² are rigidly attached at the other end to the upright rods a a beneath the spindles A', so that, the rod D being thus attached at each end 10 to the spindles A' A' by the braces D² and the bars D' D', which latter are pivoted to the upright rods a a, whenever the rod D is moved to the right or left the spindles A' A' are correspondingly moved and carry the wheels also, 15 as represented in Fig. 1 in dotted lines, thus causing a divergence in the direction of the cultivator.

D³ D⁴ are braces extending from the spindles to the cross-beam L, which serve the purpose of bracing the frame and giving steadiness to the axle-tree.

Beneath the axle-tree stock A is the whiffle-tree-bar O, which is pivoted in the middle to the stock A by the pin o. From this bar O 25 are two rods, o' o', which pass through upright

plates o'' o'' on the cross-beam L, and which have their outer ends formed into hooks upon which are hung the whiffletrees.

I claim—

1. In a wheel-cultivator, the combination, 30 with the cross-beam A, having hinges or ears, of the swiveled wheel parts a, the upper and lower brace-bars, D' D², the cross-bar D, having foot rests D³, and the lever H, substantially as and for the purpose described.

2. The combination of the drag-bars G, with bifurcated straps g, and adjustable brackets F l, with the slotted yoke-bars E, elbow-lever E', and hook K, substantially as and for the purpose described.

3. The shovel-blades B, having central ears, b, hinged to the standard-brackets, in combination with standards C, tension-rods c, and springs c', substantially as and for the purpose described.

THEO. A. PALM.
